UNITED STATES PATENT OFFICE.

MARY RIKER, OF YONKERS, NEW YORK.

BINDER ATTACHMENT FOR SEWING-MACHINES.

SPECIFICATION forming part of Letters Patent No. 514,606, dated February 13, 1894.

Application filed June 23, 1893. Serial No. 478,625. (No model.)

To all whom it may concern:

Be it known that I, MARY RIKER, a citizen of the United States, residing at Yonkers, Westchester county, New York, have invented certain new and useful Improvements 5 in Binders for Sewing-Machines, of which the following is a specification.

In binding hats by machine it is common to apply a strip to the edges of the hat rim 10 by means of a guide secured to the work-plate of the machine, which guide receives the edge of the hat rim and also doubles or folds round the latter, the strip of binding so that the rim with the strip folded upon it is 15 properly presented to the needle. An illustration of this character of guide may be found in Letters Patent to J. L. Coles, No. 112,019, dated February 21, 1871. While a 20 guide of the character described is effective to the extent of properly applying the strip to the hat rim and in relation to the needle it cannot be effectively employed in connecting together the ends of the strip an operation which must be done by hand.

25 My improvement has for its object to enable the operator not only to present the rim and binding properly to the needle as before but also to permit the end of the binding to be folded in and upon the rim and so presented to the needle that the binding can be 30 secured to the hat its entire length by means of the machine, and to this end I construct a binder, as fully set forth hereinafter and as illustrated in the accompanying drawings, in 35 which—

Figure 1 is a perspective view of my improved binder, illustrating the position of the hat rim and binding strip just prior to connecting the ends of the strip to the brim.

40 Fig. 2 is a longitudinal section of the binder.

Fig. 3 is a section illustrating the manner in which the strips are arranged prior to being presented to the needle.

The binder is provided with a plate A, 45 adapted for attachment to the work-plate of a sewing machine and with two plates each bent to a U-shape one smaller than the other the plate c, adapted to receive the edge of the rim and the plate d, which is folded on 50 the plate c, but is separated therefrom and

adapted to receive the binding, these plates c, and d, being properly supported in position, as illustrated in Fig. 2, upon the plate A in a manner too well known to need description. The inner edges of the plates c, 55 d, are on about the same vertical plane adjacent to the point where the needle x, penetrates the fabric. Heretofore the outer edges of the plates have been upon the same vertical plane, but instead of adopting this construction I make the plate c, much longer than the plate d, so that there is an extension c' of the plate c, beyond the end of the plate d and forward of said plate so as to be first met by the approaching end of the binding. 60

The hat rim is introduced into the guide c, and the strip y, of binding material is introduced between the guides c, d, as usual and the sewing is conducted in the ordinary manner until the meeting ends of the binding y are brought adjacent to the extension c' of the guide c. As the forward end of the binding, that is the loose end nearest the needle is carried over the forward end of the extension c', just after the other end of the 65 binding, which has been sewed to the rim is carried inside of said extension the operator folds in the forward loose end upon itself, as illustrated in Fig. 3, and then doubles this infolded end around the extension c' along 70 which it is carried as the rim of the hat travels in the direction of the arrow, until the infolded end passes from the end of the guide c, and onto the rim inclosing the opposite end of the binding just prior to passing beneath the needle which continues the seam along the inner edges of the binding and across the joint formed as above described. 75

It will be seen that the infolded end of the binding is thus folded close around the edge 80 of the hat and laid close onto the rim inclosing the other end of the binding and secured permanently in place by the row of stitching thereby forming a neat and durable joint not liable to open or fray without the necessity 85 of any hand sewing.

While I have described my invention in connection with the particular form of binder shown in said Coles' patent, it will be evident that the same may be used in connec- 90

tion with other forms of binders where there are two U-shaped guides with passages for the binding strip between them.

Without limiting myself to the precise construction and arrangement shown and described, I claim—

The combination in a binder of stationary U-shaped guides, one arranged within the other with an intervening space for the passage of the binding material, the forward end of the inner guide projecting in a line par-

allel with the path of movement of the fabric beyond the end of the outer guide and forming an extension c' , substantially as and for the purpose set forth.

In testimony whereof I have signed my name to this specification in the presence of two subscribing witnesses.

MARY RIKER.
